UNITED STATES PATENT OFFICE.

EMIL GOETTE, OF NEWARK, NEW JERSEY.

DESIGN FOR A PICTURE-FRAME.

SPECIFICATION forming part of Design No. 35,881, dated April 1, 1902.

Application filed March 1, 1902. Serial No. 96,344. Term of patent 7 years.

To all whom it may concern:

Be it known that I, EMIL GOETTE, a citizen of the United States, and a resident of Newark, in the county of Essex and State of New Jersey, have invented and produced a new and original Design for a Picture-Frame, of which the following is a full, clear, and exact description, reference being had to the accompanying drawings, forming a part thereof, in which—

Figure 1 is a front elevation of a picture-frame embodying the features of my design, and Fig. 2 is a section taken on the line 2 2 of Fig. 1.

The leading features of the design consist of the semiwreath of leaves A, arranged with scroll effect upon the border B, and the ribbon-tie C, appearing to secure the semiwreath of leaves to the border.

Other features of the design consist in the 20 chain of scrolls D at the outer side portion of the border figure and the vertical central leaf E and longitudinally-curled leaves E', forming a group of leaves at the upper portion of the border figure, which group of leaves closes 25 the gap in the semiwreath of leaves.

Having thus described my invention, I claim as new and desire to secure by Letters Patent—

The design for a picture-frame herein shown 30 and described.

In testimony whereof I have signed my name to this specification in the presence of two subscribing witnesses.

EMIL GOETTE.
